(57) **CLAIM**

The ornamental design for a cradle for a communication device, as shown and described.

DESCRIPTION

FIG. 1 is an isometric view of an ornamental design for a cradle for a communication device showing our new design; FIG. 2 is a front orthographic view thereof; FIG. 3 is a rear orthographic view thereof; FIG. 4 is a left side orthographic view thereof; FIG. 5 is a right side orthographic view thereof; FIG. 6 is a top orthographic view thereof; and, FIG. 7 is a top orthographic view thereof with a portion of the claimed design removed, in order to show portions of the claimed design that are obscured in FIG. 6. The broken lines shown in FIGS. 1-7 are included for the purpose of illustrating environmental elements only and form no part of the claimed design. The bottom view is omitted and forms no part of the claimed design.
